UNITED STATES PATENT OFFICE.

FREDERIC ROBERTSON, OF NEW YORK, N. Y.

DESIGN FOR FURNITURE-LEGS.

Specification forming part of Design No. **7,626**, dated August 4, 1874; application filed June 27, 1874.
[Term of Patent 3½ years.]

To all whom it may concern:

Be it known that I, FREDERIC ROBERTSON, of the city, county, and State of New York, have invented a new and original Design for Furniture-Legs, of which the following is a specification:

The nature of my design is fully represented, in front and side elevations, in the accompanying photographic illustration, to which reference is made.

The said design consists of the head A, with the crest B, chin-tuft of hair C, touching the breast or middle portion of the leg, the hairy mane D, neck-creases F, and the scroll E, on the upper portion of the leg. The design also consists of the plain scroll-border G H and the carved ornamentation I, on the lower portion of the leg. The design also consists of the

curved form of the leg, the same being the reversed curves of the end portions, as shown.

I claim as my invention—

1. The design for a leg for furniture, consisting of the head A, crest B, hair-tuft C, mane D, neck-creases F, and the scroll E, as shown and set forth.

2. The design for a leg for furniture, consisting of the scroll-border G H and the curved ornamentation I, substantially as specified.

3. The design for a leg for furniture, consisting of the reversely-curved end portions of the leg, as set forth.

FREDERIC ROBERTSON.
